UNITED STATES PATENT OFFICE.

RICHARD H. WHITEHEAD AND WILLARD E. CHAMBERLAIN, OF NEW HAVEN, CONNECTICUT, ASSIGNORS TO THE NEW HAVEN CLOCK CO., OF NEW HAVEN, CONNECTICUT, A CORPORATION.

PACKING BOX FOR CLOCKS.

Application filed February 2, 1925. Serial No. 6,231.

We do hereby declare the following, when taken in connection with the accompanying drawings and the characters of reference marked thereon, to be a full, clear, and exact description of our new and useful improvement in packing boxes for clocks, and which said drawings constitute part of this application, and represent, in—

Fig. 1 a perspective view of a packing box 10 for clock-cases, constructed in accordance with our invention.

Fig. 2 a view thereof in front elevation, on a larger scale than Fig. 1, with the box-front or cover partly broken away, showing 15 a clock installed in the box.

Fig. 3 a view thereof in vertical, transverse, central section, with a clock shown therein.

Fig. 4 a plan view thereof with the box-20 top partly broken away.

Fig. 5 a view corresponding to Fig. 3, but omitting the clock, locking-plates and wedges.

Fig. 6 a perspective view of one of the locking-plates.

Fig. 7 a corresponding view of one of the wedges.

Heretofore, great difficulty has been experienced in packing shelf-clocks having highly finished cases in individual packing-boxes, so as to avoid the mutilation of their finished surfaces in packing, transportation and unpacking, the object of our invention being to provide a packing-box with certain features, so that a clock may be installed 30 and securely held in it, and then removed 35 from it, without any possible mutilation of its surfaces.

With these ends in view, our invention consists in a packing-box having certain 40 features of construction as will be herein-after described and particularly pointed out in the claims.

In carrying out our invention, as herein shown, the box is designed for packing a 45 shelf-clock 10 of the so-called "Tambour" type, the surface of the wooden case of which is highly finished. Upon the inside of each of the box-ends 11 we fasten horizontal cleats 12 correspondingly spaced above 50 the box-bottom 13, so as to permit the extreme ends of the clock-case 10 to be inserted under them, as shown in Fig. 2, the said ends being prevented from direct contact with the cleats by cushions 14 of cork,

felt, or other non-abrasive material. These 55 cleats prevent the endwise and upward movement of the clock in the box, the height of which exceeds the height of the clock, so that there is ample clearance between the top of the clock and the top 15 of the box. 60

To prevent the lateral movement of the clock in the box, we employ two corresponding T-shaped, removable locking-members or plates 16 corresponding in length to the full width of the box from front to back 65 and formed upon their outer edges with integral keys 17 accurately adapted in length to fit between the two legs 18 at each end of the clock-case, as clearly shown in Fig. 4.

To hold these locking-pieces firmly in 70 place, as well as to press the ends of the clock firmly upward against the cushions 14, we employ two wide wedges 19 adapted to be slipped over the bottom 13 of the box, at the ends thereof, beneath the said locking-75 pieces, so as to bind the same in place and seat the ends of the clock against the said cushions. These wedges are furnished by preference with heavy cloth or canvas tabs 20, whereby they are conveniently withdrawn when it is desired to unpack the 80 clock. To prevent the possible opening of the bezel, we preferably employ a guard-strap 21 of fabric, secured to a block 22 applied to the lower face of the top 15 of 85 the box, midway of the length thereof, while the lower or free end of the guard-strap is tacked to a corresponding block 23 secured to the bottom 13 of the box midway the length thereof. As an added precaution, 90 we prefer to insert a pad 24 of corrugated paper between the back of the clock and the back 25 of the box. The front or cover 26 of the box, when applied, engages with the outer ends of the wedges and prevents 95 their outward displacement. Moreover, the ends of the locking-pieces abut against the back 25 and the front 26 of the box, and so are positively held against endwise movement. 100

Under the construction described, the clock is securely held against movement in any direction without any contact with any of its finished surfaces other than the slight contact of its ends with the non-abrasive 105 cushions applied to its end-cleats.

We claim:—

1. As a new article of manufacture, the

combination with a clock having a finished case, of a packing-box therefor, means located within the packing-box for limited nonabrasive engagement with corresponding points upon the clock-case for holding the same against endwise and upward movement in the said box, locking-plates having keys extending between the legs of the clock-case for holding the same against front and back displacement, and wedges for holding the said locking-plates in their locking positions.

2. A packing-box for clock-cases, cleats located within the said box at the ends thereof in spaced relation to the bottom thereof, T-shaped locking-plates having keys adapted in length to fit between the legs at the ends of the clock-case for holding the said plates in their locking-positions and lifting the ends of the clock-case against the said spacing-cleats.

3. A packing-box for clock-cases, cleats located within the said box at the ends thereof in spaced relation to the bottom thereof, T-shaped locking-plates having keys adapted in length to fit between the legs at the ends of the clock-case, wedges for holding the said plates in position and lifting the ends of the clock-case against the said spacing-cleats, and tabs applied to the

said wedges for the convenient removal thereof.

4. A packing-box for clock-cases, cleats located within the box at the ends thereof in spaced relation to the bottom thereof, T-shaped locking-plates having keys adapted in length to fit between the legs at the ends of the clock-case, wedges adapted for holding the said plates in position and lifting the ends of the clock-case against the spacing-cleats, and a strap fastened to the top and bottom of the box, to pass over the bezel of the clock to prevent the displacement thereof.

5. A packing-box for clock-cases, cleats located upon the inner faces of the ends of the box in spaced relation to the bottom thereof, T-shaped locking-plates having keys adapted in length to fit between the legs at the ends of the clock-case, and wedges adapted to be inserted between the said plates and the bottom of the box for holding the said plates in their locking positions and lifting the ends of the clock-case against the spacing-cleats.

In testimony whereof, we have signed this specification.

RICHARD H. WHITEHEAD.
WILLARD E. CHAMBERLAIN.
